UNITED STATES PATENT OFFICE.

HUGH T. REED, OF CHICAGO, ILLINOIS.

FOUNTAIN-PEN.

SPECIFICATION forming part of Letters Patent No. 508,182, dated November 7, 1893.

Application filed March 19, 1891. Renewed October 9, 1893. Serial No. 487,657. (No model.)

To all whom it may concern:

Be it known that I, HUGH T. REED, of Chicago, in the county of Cook and State of Illinois, have invented certain new and useful 5 Improvements in Fountain-Pens; and I do hereby declare that the following is a full, clear, and exact description thereof, reference being had to the accompanying drawings, and to the letters of reference marked thereon, 10 which form a part of this specification.

This invention relates to fountain pens of that class which are provided with a reservoir for the ink in conjunction with a point section carrying the pen and having suitable 15 means for feeding the ink to the pen, said point section being inserted in the lower end of the reservoir.

The object of my invention is to simplify the construction of the pen by dispensing with 20 the cap usually employed to close the pen when not in operation, and to this end it consists in certain features which will hereinafter be pointed out.

Referring to the drawings: Figure 1 is a 25 sectional view of a fountain pen embodying my invention in one form, the parts being in position for use in writing. Fig. 2 is a view similar to Fig. 1, showing the parts in position to close the pen when not in use. Fig. 30 3 is a plan section taken on the line 3—3 of Fig. 1. Fig. 4 is a plan section taken on the line 4—4 of Fig. 2. Fig. 5 is a sectional view showing a modified form.

In the construction shown in Figs. 1, 2 and 35 4, A represents the body of the pen, which forms the reservoir and which consists of a hollow cylinder permanently closed at its lower end.

B indicates the point section, which is shown 40 as having the form of a cylinder having two end portions, b, b', separated by a collar, b². These end portions are either cylindric or conical to adapt them to fit snugly within the open end of the reservoir A, the collar b² forming a stop to limit the motion of the point section when thus inserted, by abutting against the end of the reservoir.

C indicates the pen, which is inserted in 45 the end portion b of the point section B, this latter being provided with suitable feeding devices communicating with the reservoir and with the pen to supply the pen with ink when

in operation. The means employed for this purpose may be any particular kind, but I prefer the construction shown, which is that 55 set forth in Patent No. 449,295, issued to me March 31, 1891.

In this construction the point section B is made in the form of a hollow cylinder, open at both ends, and there are inserted in the 60 passage thus formed within the point sections, plugs D and E, one or both of which may be revoluble in the said point section. In practice I prefer to have the pen-carrying plug D fixed within the point section and in 65 this case the other plug E will be revolvable. For this purpose the plug E is slightly reduced at its end, as shown at E', the shoulder thus formed abutting against a corresponding shoulder b³ in the interior of the point section. 70 In the assembling of the parts, the plug E is first inserted in the bore of the point section, and when it is in place in the position shown, the plug D is then inserted, and this latter, being somewhat conical or tapering, will fit 75 firmly within the bore of the point section; it will thus be seen that the plug E will be held from longitudinal motion between the plug D and shoulder b³ while at the same time it may be freely rotated, being provided for 80 this latter purpose with a transverse slot e at its exposed end, in which a knife blade or other similar article may be inserted for the purpose of rotating said plug. The plugs D and E are provided with longitudinal ink 85 feeding grooves, e', in their external surfaces and constituting when inclosed by the point section, as shown in Fig. 3, ink passages by means of which the ink is conducted from the reservoir to the pen. The plug D is provided with a pen slit extending into the grooves e', and with the usual prong F for supplying the ink to the pen. It will be seen that since the grooves e' are eccentric with relation to the plugs, said grooves will no 90 longer register if the plug E is turned to a sufficient extent, and the flow of ink through the said grooves will therefore be stopped. It will also be seen that a less movement, that is, one which will not completely close 95 the said grooves, will serve to regulate the supply of ink, by varying the size of the ink-passages formed by said grooves.

In the practical operation of the pen thus

constructed, it will be seen that when the parts are in the position shown in Fig. 1, the pen is ready for use and operates in the usual manner. When it is desired to close the pen for the purpose of carrying it in the pocket, the point section is withdrawn from the reservoir, reversed, and inserted in this reversed position in the reservoir, as shown in Fig. 2. The end *b'* of the pen section, which has just been withdrawn from the reservoir, is then wiped and the pen may be placed in the pocket and safely carried without danger of spilling the ink. Since the pen will ordinarily be carried upright in the pocket and the ink passages through the point section are very small, I do not consider it in all cases necessary to provide means for closing said ink passages when the point section is reversed, but some device for this purpose is, as a rule, desirable, and I prefer that shown in Figs. 1, 2, 3 and 4. In this construction it is only necessary, when the point section has been reversed, to revolve the plug *E* slightly, in the manner hereinbefore set forth, when the ink passages will be closed and any escape of the ink from the pen absolutely prevented. Other means for effecting this closure of the ink passages may be employed, and as an instance I have shown, in Fig. 5, a construction embodying a modification of this feature. In this figure the lower end of the reservoir *A* is shown as threaded internally, while the ends *b, b'* of the point section *B* are shown as correspondingly threaded externally. This means of connection of the reservoir and point section may be employed in the construction shown in Figs. 1 to 4, or the smooth fit shown in those figures may be employed in the construction shown in Fig. 5. In this latter figure, the point section is provided with a fixed internal plug *G*, carrying the pen and having the lateral ink passages *g*, substantially as hereinbefore described. The other end of the bore of the point section is threaded internally to receive a screw plug *G'*, provided with a central ink passage, *g'*, and with a transverse slot or notch, *g''*, at its outer end by means of which said plug may be rotated. It will be seen that by rotating the screw plug *G'* in the proper direction it may be caused to advance toward or recede from the plug *G*. When the plug *G'* is in contact with the plug *G*, it is obvious that the end of each plug will close the passages of the other plug, since these passages do not register, and the flow of the ink will thus be cut off. If the plug *G'* be rotated so as to form a slight space between it and the plug *G*, this space will form a communication between the central passage *g'* of the plug *G'* and the lateral passages *g* of the plug *G*, thus permitting the ink to flow freely through the point section. It will also be seen that the size of this space between the plugs, which is determined by the position of the screw plug *G'*, regulates the flow of the ink.

Pens of this description have heretofore consisted of three essential parts, the reservoir, the point-section and the cap. In the manipulation of these three parts it is obvious that only two of them can conveniently be held in the two hands of the manipulator, the third part, generally the cap, being laid down in the first convenient place, and thereby frequently mislaid and lost. On the other hand, in my construction there are only two essential elements, the reservoir and the point section, the latter forming a closure for the reservoir in either of its positions, thus dispensing with the cap. Moreover these two essential elements are exceedingly simple in their construction, the body of the pen, which forms the reservoir, being simply a hollow cylinder open at one end, while the point section is essentially a simple cylinder adapted to receive the pen and having feeding devices. This simplicity of construction is not only a very desirable feature in itself, but it also enables me to greatly reduce the cost of manufacture.

What I claim is—

1. A fountain pen comprising a tubular body portion open at one end and closed at the other and forming the ink reservoir, and a reversible point section, each end of which fits the open end of the tubular body portion, said point section being provided with an ink passage and means for regulating the conductive capacity of said passage, substantially as described.

2. A fountain pen comprising a tubular body portion open at one end and closed at the other and forming the ink reservoir, a hollow reversible point section, each end of which fits the open end of the tubular body portion and one end of which is closed save for a relatively small ink passage, a rotatable plug fitting the interior of said section and provided with an ink passage normally forming an extension of the passage through the closed end of the section, the adjacent ends of said passage being at one side of the axis of the rotatable plug whereby communication between said passages may be cut off by rotating the plug, substantially as described.

3. A fountain pen comprising a tubular body portion open at one end and closed at the other and forming the ink reservoir, a hollow reversible point section, each end of which fits the open end of said tubular body portion, a stationary and a rotatable plug fitting the bore of said point section with their adjacent ends in contact and a longitudinal groove on the surface of each plug forming a passage for the ink, substantially as described.

In testimony that I claim the foregoing as my invention I affix my signature in presence of two witnesses.

HUGH T. REED.
